HANDLE FOR GUN CLEANING ROD

Edwin A. Volker, Palmyra, N.J., and Alma R. Hartmann, Abington, and Frank Dreyer, Levittown, Pa., assignors to Frank A. Hoppe, Inc., Philadelphia, Pa., a corporation of Pennsylvania

Filed Aug. 18, 1965, Ser. No. 86,624

Term of patent 14 years

(Cl. D30—1)

FIGURE 1 is a perspective view of a handle for gun cleaning rod embodying our design;

FIGURE 2 is a top plan view thereof;

FIGURE 3 is a bottom plan view thereof;

FIGURE 4 is a front elevational view thereof; and

FIGURE 5 is a side elevational view.

We claim:

The ornamental design for a handle for gun cleaning rod, substantially as shown.
